PICKLE PACKING MACHINE

Charles G. Lang, Baltimore, Md., assignor to C. C.
Lang & Son, Inc., Baltimore, Md.

Application July 18, 1938, Serial No. 219,853

5 Claims. (Cl. 226—14)

This invention refers to machines for packaging pickles and more particularly to a device for packing pickles in jars, especially of the cucumber type. It has among its objects to provide a device that will enable pickles of this nature to be closely and quickly packed into bottles or containers of the conventional type; to have the functions performed with convenience to the operator; and other objects that will become apparent as the invention is more fully set forth.

The packing of pickles of the cucumber type is usually performed by hand, and has to be done with care to meet the special conditions which this vegetable brings about, through its shape and variable body growth. It is difficult to pack the pickles into bottles or containers which are usually used, because of their lack of uniformity, slipperiness and resiliency. This situation causes considerable loss of time, damage to the pickles, and inartistic line-up of the pickles in the bottles. This invention removes the objectionable part of the packing. It permits the pickles to be packed closely and in proper alignment. It prevents undue handling of the pickles by the operator, and pickles are inserted in the containers quickly and conveniently. The device is semi-automatic and requires no motor power for ordinary purposes.

In the drawing, which illustrates an embodiment of this invention:

Figure 1 is a side view in elevation of a pickle packer, with portions broken away, to show the interior construction.

Figure 2 is a front view of the device indicated in Figure 1.

Figure 3 is a detail of a pickle jar or bottle with the pickles packed in same by the pickle packer, to show in a general way how the device places the pickles in the container.

Figure 4 indicates a modified form of filler cylinder used in this device, having an opening in its wall, to permit packing from the exterior.

Figure 5 is an end view of Figure 4.

Similar reference characters refer to similar parts throughout the drawing.

In the construction indicated 1 represents the base of the device. This base is preferably made as shown, the extension piece 2 being arranged to form an under-support and attachment for resting it on a table 3, bench or other means for conveniently positioning the device for the operator's use. The holes 4 in the extension piece allow screws or bolts 6 to be fastened through it, to the table 3.

55 The upper portion of the base has holes 5 for

bolts 7 which serve to secure a holder 8 to it, through the holes 9 in the latter. This holder is provided with a bell-shaped portion 10 which projects from the base and is screw-threaded internally. A shell plunger member 11, having external screw threads 12 at one end portion 13 is of cylindrical form and hollow, and designed to take a coil spring 14 of the compression type. The walls of the cylinder are slotted at 15 through the greater length, to permit the cross-heads 16 to travel longitudinally in same, and in working contact with the coil spring 14. The end portion 17 has a cap 18 for closing the external projecting end as indicated. A filler cylinder 19 slides over the circumferential exterior of the plunger 11, and is guided in its travel by the crossheads 16 which are attached to it by the screws 20. The filler cylinder is made large enough to take a suitable number of pickles 21 of the selected length, permitting their end portions 22 to project a slight amount. The projecting amounts allow the pickles to project sufficiently to make them enter into a jar 23 to be filled and packed. The jar or bottle is brought up to the open mouth 25 and held thereby hand or with the spring clamps 24 which are fastened on by the screws 20.

In the modified form of filler cylinder or head shown in Figure 4, a open slot 30 closable by a hinged slide 26 in the upper portion of the filler 30 cylinder, permits the pickles to be inserted at the top instead of through the mouth 25. In this case, they may be dropped in place, instead of being pushed in from the front.

The method of operation is simple, consisting in three main steps. In the first step, the pickles are stacked in the filler cylinder as closely as possible. They stay in this position because the wall of the filler cylinder surrounds and compresses them. The pickle jar or bottle is then brought against the end surface 27 of the filler cylinder, and held there by the operator. The clamp springs 24 also support the jar by pressing against its exterior surface and serve to align same accurately with the mouth of the filler cylinder. The operator then, in the third step, forces the jar against and onto the plunger, against the tension of the coiled spring 14. While this is being done, the plunger presses against the bunched pickles and causes them to enter the jar and keep their stacked form. They pass in the jar and stack in the bottom row; second row, or last row as the case may be. This leaves the pickles tightly filling the jar in rows which look neat and regular. The jar is then

- withdrawn, allowing the filler cylinder to return to its normal position under the tension of the spring 14. Then, more pickles are placed in the filler cylinder, for packing the jar ready for same.
- 5 When the filler cylinder is pushed back, it slides over the exterior surface of the plunger and is guided by the cross heads 16 moving in the slots 15. The limit of the travel at each end is determined by the ends 28 and 29 of the slots. The 10 length of the plunger is determined by the length of the jar with which the device is used. The travel of the filler cylinder is determined by the position the pickles are to take in the jar. If the pickles are for the bottom row on the bottom 15 of the jar, the travel of the filler cylinder to place them, is longer than the rows nearer the top of the bottle.

This process is considerably speedier than the general method of placing the pickles in the jar 20 by using the fingers. It avoids the loss of time and patience required by existing methods, and packs the vegetables more closely and uniformly. It reduces the amount of skill required of the operator and makes the work more agreeable.

25 The parts are accessible for inspection, repair, or cleaning, and may be readily dissembled for removal, changing, or storing away.

While but two forms of the invention are shown in the drawing, it is not desired to limit 30 this application to such particular construction, or in any other way, otherwise than limited by the prior art, as it is appreciated that other constructions may be used, that will use the same principles and come within the scope of the appended claims.

Having thus described the invention, what is claimed is:

1. A pickle packer comprising in combination, a plunger, a filler head for pickles mounted on the plunger and adapted to slide thereon and force the pickles out of same in stacked rows, and a resilient member for tensioning the filler head disposed in the plunger.
2. A pickle packer comprising in combination, a plunger, a filler head for pickles mounted on the plunger and adapted to slide thereon and force the pickles out of same in stacked rows, a

resilient member for tensioning the filler head disposed in the plunger, and an opening in the filler head for allowing the pickles to be stacked in the filler head exteriorly to the same.

3. A pickle packer of the class described comprising in combination, a filler head for stacking pickles therein, a plunger cylinder adapted to support the filler head and slide therein, means in the cylinder for guiding the filler head thereon in its travel, a cap on the plunger arranged to fit in the filler head and make contact with the pickles therein and force same therefrom, means for aligning a jar for the pickles on the end portion of the filler head to receive the pickles expressed therefrom, a support for the plunger, resilient means in the plunger for tensioning the filler head and the aforementioned means.

4. A pickle packer of the class described comprising in combination, a filler head for stacking pickles therein, a plunger cylinder adapted to support the filler head and slide therein, means in the cylinder for guiding the filler head thereon in its travel, a cap on the plunger arranged to fit in the filler head and make contact with the pickles therein and force same therefrom, means for aligning a jar for the pickles on the end portion of the filler head to receive the pickles expressed therefrom, a support for the plunger, resilient means in the plunger for tensioning the filler head and the aforementioned means, means for adjusting the plunger cylinder in said support and for fastening same in position.

5. A packer having a plunger cylinder and supporting member therefor, slots being provided in the wall of said cylinder, a filler cylinder slidably mounted on the exterior surface of the plunger cylinder, cross heads attached to the filler cylinder and travelling in a reciprocating movement in said slots, a coil spring in the plunger cylinder making contact with the cross heads and tensioning the same, clamps on the filler cylinder for aligning the pickle jar thereon whereby the travel of the filler head on the plunger will force pickles from the filler head into the jar in stacked rows.

CHARLES G. LANG.
